(57) **CLAIM**

The ornamental design for a bag, as shown and described.

DESCRIPTION

FIG. 1 is a perspective view of a bag showing my design; FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof; and,

FIG. 8 is a perspective view showing a bag in use.

The smaller broken lines shown in FIGS. 1-8 represent conventional stitching.

The larger broken line showing in FIG. 8 is for illustrative purposes only and forms no part of the claimed design.
